DESIGN FOR A HANDBAG FRAME OR SIMILAR ARTICLE

Ralph C. Ewing, New York, N. Y.

Application September 1, 1945, Serial No. 121,782

Term of patent 3½ years

(Cl. D87—3)

To all whom it may concern:

Be it known that I, Ralph C. Ewing, a citizen of the United States of America, residing in New York city, county of New York, and State of New York, have invented a new, original, and ornamental Design for a Handbag Frame or Similar Article, of which the following is a specification, reference being had to the accompanying drawing, forming part thereof, wherein,

The rear of the handbag frame or similar article is substantially the same in appearance as the front, except for the omission of the closure member.

I claim:

The ornamental design for a handbag frame or similar article, substantially as shown and described.

RALPH C. EWING.
